UNITED STATES PATENT OFFICE.

FRANCIS K. FASSETT, OF ST. LOUIS, MISSOURI, ASSIGNOR, BY MESNE ASSIGNMENTS, TO WILLIAM MAXWELL SCOTT, OF PHILADELPHIA, PENNSYLVANIA.

SWITCH.

No. 329,917.

Specification of Letters Patent.

Patented Aug. 28, 1906.

Application filed April 27, 1904. Serial No. 205,185.

To all whom it may concern:

Be it known that I, FRANCIS K. FASSETT, a citizen of the United States, residing at St. Louis, State of Missouri, have invented a new and useful Switch, of which the following is a specification.

My invention relates to electrical switches, and more particularly to that type in which the contacts separate under oil or other suitable insulating material whereby electric currents of high pressure and considerable volume may be broken with a minimum of sparking or arcing.

My invention resides also in controlling or operating devices whereby the switch may be automatically tripped or released and whereby the operator is robbed of control of the switch if he attempts to close the switch during the existence or continuance of an undesired or abnormal electrical condition.

My invention resides also in other features hereinafter described, and pointed out in the claims.

For an illustration of a form my invention may take reference is to be had to the accompanying drawings.

Figure 1 is a top plan view of the switch and its controlling mechanism. Fig. 2 is an end elevation of the switch and its operating mechanism. Fig. 3 is a front elevation, partly in section, of the controlling and operating mechanism. Fig. 4 is a side elevational view, the oil-switch being shown partly in section. Fig. 5 is an enlarged view of the operating mechanism showing the parts in position immediately after being tripped. Fig. 6 is a view similar to Fig. 5, showing the position of the parts when the switch has reached open position. Fig. 7 is an enlarged front elevational view showing details of the control mechanism. Fig. 8 is a horizontal sectional view through the base showing mode of connection of the supporting - bracket. Fig. 9 is a cross-sectional view of the line 9 9 of Fig. 3. Fig. 10 is an enlarged detailed view of the calibrating device. Fig. 11 is a sectional view showing method of supporting the porcelain portion of the switch upon the cover of the fluid-receptacle. Fig. 12 is an enlarged side elevational view of a laminated contact-block and a portion of the bridging-contact adapted to engage the same. Fig. 13 is a view similar to Fig. 12 showing the

bridge in engagement with the laminated contact.

Referring to the drawings, a vertical base or switchboard 1 of suitable insulating material, such as marble or slate, has secured to the base thereof the brackets 2 and 3, the bolts 4 and 5 passing through the ears 6 and 7, respectively, of the brackets and through the switchboard 1. The brackets 2 and 3 are provided with the inturned flanges 8 and 9, which fit over the edges of an insulating-block 10, preferably of slate or marble, the flanges 65 being secured to the block 10 by the bolts 11 and 12, the heads of which are preferably countersunk in recesses in the block 10.

Each of the brackets 2 and 3 is provided with an arm 13, having the horizontal ear or flange 14 approximate to its outer end, and each of the brackets 2 and 3 is provided with an arm 15, extending upwardly and provided at its upper end with a horizontally-extending hole to form a bearing to receive the horizontally-extending rod 16, forming a bearing for parts hereinafter referred to. The brackets 2 and 3 support three sheet-metal oil-tanks or receptacles 17, each of which is provided with perforations 18 in its walls near the top thereof. The metallic plate 19 forms a cover for the receptacles and has upwardly-turned flanges 20 around its edge and strengthened by ribs 21. In the center of the cover are three upwardly-extending flanges 23, through which extend vertical holes for purposes hereinafter described.

Lugs 24 and 25 upon the cover-plate 19 support the vertically-extending rods 26 and 27, which latter pass through the horizontally-disposed bar 26 and serve as vertical guides for the vertical movement of the bar 28, which is connected by the links 30 to the bell-crank levers 31, pivoted on the shaft 16. Through the three flanges 23 upon the cover 19 are adapted to reciprocate three vertical rods 29, of wood or other insulating material, which are hung upon the bar 28 by stirrup 29^a, fastened on the top of each rod 29 and having the screw 29^a for adjustment purposes.

Three blocks 32, of porcelain or other insulating material, suitably cast or formed are supported by and secured to the under side of the covered plate 19. Each porcelain block 32 consists of a hollow depending portion 33, which is completely immersed in the

55

105

oil in tanks 17. Shoulders 34 and 35 support plates 36 and 37, constituting clamps between which are secured the laminæ of the laminated contacts 45 and 46. Bolts 38 project through these clamps and through the thickened portions of the shoulders 34 and 35 and engage plates 39 in the bottoms of the recesses in the upwardly-projecting tubular portions 40 of the porcelain blocks 32. These recessed projections 40 extend through the cover 19 and are provided with caps 41, having openings 42, through which the insulated cables or leads 59 60 project. The cables or circuit-leads are electrically and mechanically connected to the binding-posts 43, projecting up into the recesses of the portions 40. The lower ends of the posts 43 are adapted to receive bolts 44, which extend through the laminæ of the contact-terminals 45 and 46. If desired, the laminæ may be secured to each other by means of rivets or other fastening devices. The tubular projections 40 of the porcelain blocks 32 are joined by the web portion 47. This web carries a depending tubular partition, the tubular opening therein being in alignment with the opening 22 in the cover-plate 19. Through this tubular opening extends the rod 29, which carries at its lower end the bridging member movable contact 48. The tubular partition 47 is slotted, and through the slot extends the bridging member 48, whose surfaces are adapted to engage the ends of the laminæ of the contacts 45 and 46. The angle of the contact-surface on the member 48 and of the contacts 45 and 46 are somewhat different, as shown in Fig. 12. On the clamping-plates 37 are provided shunt-contacts 49, which are adapted to be engaged by the movable shunt-contacts 51, carried by the resilient member 50, secured to the rod 29.

Any gases formed by arcs or other effects are permitted to pass up through the perforated web 47 and out through the openings 18 in the walls of the tanks 17. To facilitate the discharge of gases, the top surface of each web is provided with transverse grooves 52, which are in communication with ducts 48, which communicate with the hollow portion 50 of the block 32. Each insulating-block 32 is secured to the cover-plate 19 by means of bolts 53, whose nuts 54 engage in recesses 55 in the block 32. (See Fig. 11.) Each tank 17 is secured to the cover-plate 19 by means of a pin 56, which extends through one of the openings 18, the cover-plate having a slot 57, which receives the eyebolt 58.

There being three complete switches shown each is independently adjustable with respect to the bar 23 by the stirrup and adjusting-screw at the top of each rod or stem 29. By suitably adjusting these screws 29^a the bridging members 48 may all be caused to come to full circuit-closing position at the same time and to break the circuit at the same

time. Power is transmitted to the stems or rods 29 by the bell-crank lever 31 through the medium of the handle and parts hereinafter described.

Bracket 61 is secured by suitable bolts 62 to the front of the switchboard 1. Between the horizontal portions 63 and 64 of the bracket 61 are supported solenoids 65 and 66. A threaded tubular guide 67 is secured to the lower member of each pair of solenoid-supports, the tubular guide having slots 68 therein. Secured within the tubular guide 67 and having a projection 69 is a nut 70, adapted to be adjustable vertically in the guide 67 by the threaded rod 71. The rod is provided with oppositely-disposed projections 72, normally seated in a groove 73 in the bottom of the guide, so that the rods 71 will normally be non-rotatable. By lifting the projections 72 out of groove 73 the rods 71 can be rotated to adjust the nut toward or away from the bottom of the guide. The nut acts as a support for the reciprocating solenoid-core 74, so that by adjusting the nut the electrical condition to which the switch is to respond may be determined.

The operating handle or actuator 75 is pivoted between the ears 76 and 77 on the bracket 61. At its lower portion the operating-lever 75 is bifurcated, comprising the flat blades or plates 78, slotted at 79. One end of the link 80, which is pivotally secured at 81 to one arm of the bell-crank lever 31, (the link 80 is insulated from the bell-crank lever by the material 82,) has a sliding connection with operating-handle 75 in the slots 79. As viewed in Fig. 4, the slots 79 are inclined upwardly and outwardly from the switchboard 1, and the pin or roller carried by the link 80 and engaging in the slots 79 is held at the inner end of the slots by trigger mechanism, consisting of the small lever 83, pivoted to plates 78 and carrying at its one end the roller 84. A spring 86 is wound about its pivot and is so applied as to force the trigger 83 against the adjustable stop 85, also carried by the plates 78. The end of the lever or link 80, which carries the pin or roller engaging in the slots 79, has its lower corner rounded off, while its upper corner is retained rectangular. The bracket 61 supports the horizontally-disposed shaft 87, having secured thereto the arms 88 and 89 and the tappet 90 and the manual 91. In the top of the solenoid are provided the plugs 95 and 96, within which reciprocate the plungers 93 and 94, adapted to receive the impacts from the solenoid-cores.

With the parts in circuit-closing position, as shown in Fig. 4, the roller 84 engages the end of the link 80, and because of the stop 85 the lever or trigger 83 cannot rotate under the pressure exerted upon it, and in consequence holds the lever 80 in the ends of the slots 79 nearest the switchboard. In this

position the tendency is to rotate the handle 75 in a counter clockwise direction, as viewed in Fig. 4. When an undesired electrical condition obtains, the solenoid-cores are drawn upwardly by magnetic action, and either the arm 88 or the arm 89 is struck a blow, rotating the shaft 87 and the tappet 90 in a clockwise direction, as viewed in Figs. 4 and 5. The tappet 90 thus causes the trigger or lever to rotate in a counter-clockwise direction about its pivot, thus moving the roller in a substantially downward direction, and allows the link 83 to ride with its rounded-off corner past the roller 84, and the link 80 then passes to the outer end of the slots 79 to the position shown in Fig. 5. The opening movement has, however, not been completed when this position is reached, for when the link 80 reaches outer end of the slot 79 a slight further movement occurs and the handle 75 falls to an approximately horizontal position. It is the weight of the stems 29 and the bridging members carried thereby that supplies the force for the opening movement, though the spring 92 may be employed, if desired, to aid in throwing the handle 75. In the opening movement the bridging members 48 first separate from the laminated contacts 45 and 46, and later the movable shunt-contacts 51 separate from the fixed shunt-contacts 49, so that the final arc occurs at the shunt-contacts which are easily and cheaply renewable and prevents blistering or melting of the main contacts. As well understood, the insulating fluid, such as oil, assists in minimizing arcing, so that in a switch of moderate mechanical dimensions a high-pressure electric current may be successfully broken. When the parts have reached full open position, as shown in Fig. 6, the spring 86 has returned the trigger 83 against its stop 85, and the outer end of the link 80 is again at the inner ends of the slots 79. To close the switch, the handle or actuator 75 is raised by the operator and the roller 84 passes around the corner of the link 80 until it strikes its flat surface, and in so moving the link 80 is forced inwardly through the switchboard, and the bridging members 48 are again raised toward circuit-closing position. When the parts are finally in circuit-closing position, as shown in Fig. 4, the roller 84 is in engagement with the flat or straight end of the link 80. The link 80 and the lower portion of the handle 75, comprising the plates 78, form a toggle which is overtravelled when the parts are in circuit-closing position, the toggle being broken when the circuit-breaker is tripped. This toggle might be described as one in which the pivot connecting two links or levers of the toggle is a shifting-pivot, the trigger 83 being adapted to confine the shifting-pivot at certain periods to form a toggle and adapted to release it at other times. If

it is attempted to close the switch during the continuance or existence of an abnormal or undesired electrical condition at first contact, a solenoid-core is drawn upwardly and actuates the tappet 90 to tilt the lever 83, thus breaking the mechanical connection between the handle 75 and the link 80. This permits the bridging-contacts 48 to again drop and open the circuit. This "non-closable" feature—that is, the robbing of the operator of control during the existence or continuance of an undesired electrical condition—is in this mechanism constituted by toggle links or levers, whose common pivotal connection is a shifting one. When the pivotal connection is in one position, the links or levers are adapted to slightly overtravel, so as to constitute a lock for the switch, and when allowed to shift the links or levers no longer form a toggle. 85

What I claim is—

1. In an electric switch, the combination with an insulation-support, of laminated contacts having free edges of unequal lengths to form inclined faces, a hollow partition-wall between said contacts, a bridge coöperating with the free edges of said laminated contacts, and a stem for supporting the bridge in position and for moving the same into and out of operative relation with the contacts, 95 said stem projecting through said hollow partition, substantially as described.

2. In a multiple switch, the combination with a carrying-rod, of connecting-bridges loosely suspended from said rod, and means for independently adjusting said bridges with respect to said rod, substantially as described.

3. In a multiple switch, the combination with laminated contacts whose free edges are unequal in length, of bridges coöperating with said free edges and having inclined faces at different angles from the planes in which the unequal edges of the laminations of the contact-blocks lie, stems for carrying said bridges, slotted members on said stems, set-screws in said slotted members, a rod passing through said slotted members for supporting the same through the medium of said set-screws, whereby each stem and the bridge supported thereby is independently adjustable with respect to said rod, substantially as described. 110 115

4. In an electric switch, the combination with an operating-handle having an obliquely-arranged slot, of a link operatively mounted in the slot of said handle and connected to the movable contact of the switch, a trigger on said handle adapted to engage said link and means for controlling said trigger. 120

5. In an electric switch, the combination with an operating-handle having an obliquely-arranged slot, of a link operatively mounted in the slot of said handle, a movable contact connected to said link, a trigger 130

mounted on the handle and adapted to engage said link to hold it at one end of the slot, whereby the movable contact and the handle may be mechanically connected; and 5 electroresponsive means for controlling said trigger, substantially as described.

6. In an electric switch, the combination with fixed and movable contacts, of a slotted operating-handle, a link mounted in the slot 10 of said handle and connected to the movable contact member and a trigger mounted on said handle and adapted to engage said link to hold it in such position that the movable contact is in engagement with the fixed contacts. 15

7. In an electric switch, the combination with fixed and movable contacts, of a slotted lever, a link mounted in the slot of said lever and connected to the movable contact member, a trigger mounted on said lever and adapted to engage said link to hold it in such position that the movable contact is in engagement with the fixed contacts, and electroresponsive means for operating said trigger, substantially as described. 25

8. In an electric switch, the combination with fixed and movable contacts, of a slotted operating-handle, a link mounted in the slot of said handle and connected to the movable 30 contacts, a trigger mounted on said handle and adapted to engage said link to hold it in such position that the movable contact is engaged with the fixed contacts, and manually and electrically operable means for operating 35 said trigger, substantially as described.

9. In an electric switch, the combination with a movable contact, of a link operatively connected to said movable contact, a slotted handle, a trigger adapted to engage said link 40 to hold it at one end of said slot, whereby the movable contact is held in engagement with its coöperating fixed contacts, and means for actuating said trigger to disengage said link, whereby said link may travel to the other 45 end of said slot to actuate said handle, said handle being adapted to thereafter move independently of said link.

10. In an electric switch, the combination with a movable contact, of an operating-handle 50 normally locked thereto, means for unlocking the movable contact from the operating-handle and permitting independent movement of said movable contact without disturbing the position of said handle, and 55 means for limiting said independent movement of movable contact with respect to said handle, whereby said handle is thrown to open position by said movable contact.

11. In an electric switch, the combination 60 with a movable contact, of an operating-handle normally connected therewith, means for breaking coöperative connection between said handle and said movable contact and permitting the movable contact to move independently of the handle, and a stop on said

handle engaged to throw said handle to open position.

12. In an electric switch, the combination with a movable contact, of an operating-handle normally connected to said movable contact, means for breaking coöperative connection between said movable contact and the handle and permitting the movable contact to initially move without disturbing the position of the handle, and means on said handle 75 engaged at the final movement of said movable contact to move said handle to position for reconnection with said movable contact. 70

13. In an electric switch, the combination with movable and fixed contacts, of an operating-handle, a trigger carried by said handle and adapted to normally maintain the handle and the movable contact in coöperative relation, means for breaking the operative connection between the handle and 80 movable contact, whereby the movable contact is permitted to break the circuit, and means on said handle engaged at the final movement of the movable contact to move said handle, whereby said trigger may reconnect said handle and the movable contact, 85 substantially as described. 90

14. In an electric switch, the combination with a movable contact member, of a handle for operating said member and normally 95 locked in coöperative relation therewith, and means for temporarily unlocking the handle from said contact member to open the circuit, whereby in moving to open position said contact member operates the handle to reestablish engagement between it and said handle, 100 substantially as described.

15. In an electric switch, the combination with a vessel containing an insulating fluid, of an insulation-support partially submerged in 105 said fluid, contacts carried by the insulation-support, an immersed partition formed integral with the insulation-support, and arranged between the contacts, a bridge movable with respect to the contacts, and a rod for supporting said bridge, said rod passing through 110 an opening in the partition, substantially as described. 115

16. In an electric switch, the combination with a vessel containing an insulating fluid, 115 of an insulation-support partially submerged in said fluid, submerged contacts carried by said insulation-support, a submerged bridge movable with respect to said contacts, a yielding means movable with the bridge for connecting the contacts after the circuit is opened by the bridge, and means on the bridge for moving the submerged secondary contact means out of engagement with the contacts after the bridge is moved out of engagement with the contacts, substantially as described. 125

17. In an electric switch, the combination with a movable contact member, of an operating-handle normally locked in coöperative 130

relation therewith, a trigger for unlocking said contact member and permitting its movement independently of the handle, whereby it moves freely without having to overcome the 5 resistance offered by the handle, and means on said handle engaged at the end of said independent movement, whereby said handle is moved to position to permit said trigger to again lock said contact member and 10 handle together, substantially as described.

18. In an electric switch, the combination with a movable contact member, of a handle normally connected therewith for moving said contact member to close the circuit, 15 means on the handle for breaking co-operative relation between said handle and contact member to open the circuit, said opening movement being independent of the handle, and means on said handle engaged when the 20 circuit is open to throw said handle to position to permit its reconnection with said contact member, substantially as described.

19. In an electric switch, the combination with a vessel containing an insulating fluid, 25 of an insulation-support forming a cover for said vessel and provided with an integral partition, contacts on each side of the partition, said partition and contacts extending down into the insulating fluid, and a bridge 30 projecting through the partition and movable into and out of engagement with the contacts, substantially as described.

20. In an electric switch, the combination with a vessel containing an insulating fluid, 35 of an insulation-support forming a cover for the vessel and having a hollow slotted partition, contacts supported by said insulation-support on the respective sides of the partition, an element movable in the hollow partition, a bridge carried by said element and 40 projecting through the slots in the partition and actuated by the movable element to be moved into and out of engagement with the contacts, substantially as described.

45 21. In an electric switch, the combination with a vessel containing an insulating fluid, of an insulation-support in the fluid having a hollow immersed portion, and hollow projections extending above the level of the insulating fluid, a web connecting the hollow projections, a hollow partition carried by the web, binding-posts extending through portions of the insulating-support on each side of said partition, contact-blocks carried by 50 the binding-posts, a reciprocating rod movable in the hollow partition, and a bridge carried by the rod and projecting through the partition for engagement with the contact-blocks, substantially as described.

60 22. An insulation for electric switches comprising a block having a lower hollow portion, upper hollow projections, a perforated web connecting the hollow projections, and a slotted hollow partition carried by the 65 web, substantially as described.

23. In an electric switch, the combination with a base, of a vessel containing an insulating fluid, contacts immersed in the fluid, a bridge movable in the fluid to close the contacts, a bridge-stem, a lever supported by 70 said base and connected to said stem, an actuating-lever carried by said base and provided with an obliquely-arranged slot, a link connection pivotally secured to the first-named lever and having a part to work in the slot of the actuating-lever, and means for maintaining said part in a state of rest in the slot, substantially as described.

75 24. In an electric switch, the combination with a base, of a vessel containing an insulating fluid, contacts immersed in the fluid, a bridge movable in the fluid to close the contacts, a bridge-stem, a lever supported by 80 said base and provided with an obliquely-arranged slot, a link connection pivotally secured to the first-named lever and having a part to work in the slot of the actuating-lever, and pivoted means for maintaining said part in a state of rest in the slot, substantially as 85 described.

90 25. In an electric switch, the combination with a base, of a vessel containing an insulating fluid, contacts immersed in the fluid, a bridge movable in the fluid to close the contacts, a bridge-stem, a lever supported by 95 said base and connected to said stem, an actuating-lever carried by said base and pivoted with an obliquely-arranged slot, a link connection pivotally secured to the first-named lever and having a part to work in the slot of the actuating-lever, and spring-pressed pivoted means for maintaining said part in a state of rest in the slot, substantially as described.

95 26. In an electric switch, the combination with a base, of a vessel containing an insulating fluid, contacts immersed in said fluid, a bridge movable in said fluid to close the contacts, a bridge-stem, a lever supported by 100 said base and connected to said stem, an actuating-lever carried by said base and provided with a slot, a link connection pivotally secured to the first-named lever and having a part to work in the slot of said actuating-lever, and means on said actuating-lever for 105 maintaining said link in a state of rest with relation to the slotted part of the actuating-lever, said means being movable out of engagement with said link to permit movement thereof along the line of said slot to throw the 110 actuating-lever, substantially as described.

115 27. In an electrical switch, the combination with a base, of a vessel containing an insulating fluid, contacts immersed in said fluid, a bridge movable in said fluid to close said contacts, a bridge-stem, a lever supported by 120 said base and connected to said stem, a handle carried by said base and provided with a slot, a link connection pivotally secured to the first-named lever and having a part to 125 130

- work in said slot of said handle, a trigger for releasing said link from said handle, and an electrically-operated means for actuating said trigger, substantially as described.
- 5 28. In an electric switch, the combination with spaced contacts, of means for bridging said contacts, a bridge-stem carried by said means, a lever connected to said stem, a link connected with said lever, a pivoted and slotted element engaged by one end of said link and having a throw when said link moves along said slot, a trigger for releasing said link, a rock-shaft, crank-arms on said rock-shaft for releasing said trigger from engagement with said link, and means for actuating said rock-shaft, substantially as described. 70
- 10 29. In an electric switch, the combination with spaced contacts, of means for bridging said contacts, a bridge-stem carried by said means, a lever connected to said stem, a link connected to said lever, a pivoted and slotted element engaged by one end of said link and having a throw when said link moves along said slot, a trigger for releasing said link, a 75 rock-shaft, crank-arms on said rock-shaft for releasing said trigger from engagement with said link, and means for actuating said rock-shaft including an electrically-controlled tap-pet device, substantially as described. 80
- 15 30. In an electric switch, the combination with spaced contacts, of means for bridging said contacts, a bridge-stem carried by said means, a lever connected to said stem, a link connected to said lever, a pivoted and slotted element engaged by one end of said link and having a throw when said link moves along 85 said slot, a trigger for releasing said link, a rock-shaft, and a crank-arm on said rock-shaft for releasing said rock-shaft, substantially as described. 90
- 20 31. In an electric switch, the combination with a vessel containing an insulating fluid, of a chambered insulation-support arranged in said vessel and having depending marginal flanges at its sides, a hollow partition-wall for dividing the flange-formed chamber into compartments, stationary contacts in the several compartments, a bridge coöperating with said stationary contacts, and a stem extending through said hollow partition-wall upon which said bridge is mounted, substantially as described. 95
- 25 32. In an electric switch, the combination with a vessel containing an insulating fluid, of a cover for the vessel, an insulation-support having hollow bosses extending upwardly through said cover, said insulation-support also having depending marginal flanges extending down into said fluid, a centrally-arranged hollow partition-wall integral with said insulation-support, stationary contacts mounted on ledges in vertical alignment with said upwardly-extending bosses, a bridge coöperating with said stationary contacts, and a stem extending through said hollow 100
- 30 partition-wall and upon which stem said bridge is mounted, substantially as described. 105
33. In an electric switch, the combination with a vessel containing insulating fluid, of stationary contacts immersed in said fluid, an insulation-piece having marginal flanges around said stationary contacts, a partition-wall integral with said flanges and arranged between said stationary contacts, and means for opening and closing the circuit through 110 said stationary contacts, substantially as described. 115
34. In an electrical switch, a hollow insulating-support, a partition dividing the cavity into chambers, a contact mounted in each chamber, a bridging contact extending through said partition, and means for operating said bridging member located within said partition. 120
35. In an electrical switch, a movable contact member, levers for operating said contact member, a shiftable pivot for connecting said levers together to form a toggle, and a trigger on one of said levers for confining said pivot. 125
36. In an electrical switch, a movable contact member, a lever for communicating movement to said contact member, an actuator-lever, means for connecting said levers together to form a toggle, and means upon one of said levers for locking said levers in toggle relation. 130
37. In an electrical switch, a movable contact member, a lever for communicating movement to said contact member, an actuator-lever, a guide for permitting free movement of said levers with respect to each other, and means upon one of said levers for locking said levers together to form a toggle. 135
38. In an electrical switch, a movable contact member, a lever for communicating movement to said contact member, an actuator-lever having a slot in which said first-mentioned lever is movable, and means for barring said first-mentioned lever in predetermined position in said slot, whereby said levers are connected together to form a toggle. 140
39. In an electrical switch, a movable contact member, a lever for communicating movement to said contact member, an actuator-lever, said levers being adapted to move freely with respect to each other, a guide for permitting said free movement, and means for locking said levers in predetermined position with respect to each other, whereby said actuator-lever may operate said contact member. 145
40. In an electrical switch, a movable contact member, a lever for communicating movement to said contact member, an actuator-lever, said levers being freely movable with respect to each other, a guide for permitting said free movement, and means for confining said levers in predetermined posi- 150

- tion with respect to each other to form a toggle.
41. In an electrical switch, a movable contact member, a lever for communicating movement to said contact member, an actuator-lever, means for connecting said levers together to form a toggle, and electroresponsive means for breaking said connection upon attempted movement of said contact member into normal position during the existence or continuance of predetermined electrical conditions.
42. In an electrical switch, means for operating a movable contact member comprising toggle-levers operatively connected with each other, and means for breaking the operative connection between said toggle-levers.
43. In an electrical switch, a toggle, a movable contact member operatively connected with a link of said toggle, a handle operatively connected with another link of said toggle, means for operatively connecting said toggle-links with each other, and means for breaking the operative connection between said toggle-links.
44. In an electrical switch, a movable contact member, a toggle having operative connection with said contact member, means engaging a toggle-link to maintain it in operative connection with another toggle-link, and electroresponsive means for breaking the operative connection between the toggle-links.
45. In an electrical switch, a movable contact member, a toggle having operative connection with said contact member, and means for preventing the movement of said contact member into normal position during the existence or continuance of predetermined electrical conditions comprising electroresponsive means for breaking the operative connection between the links of said toggle.
46. In an electrical switch, a toggle, a movable contact member, having operative connection with a link of said toggle, an operating-handle having operative connection with another link of said toggle, means engaging a link of said toggle to maintain it in operative relation with another link of said toggle, and means for preventing the movement of said contact member into normal position during the existence or continuance of predetermined electrical conditions comprising electroresponsive means for breaking operative connection between said toggle-links.
47. In an electrical switch, a toggle, a movable contact member having operative connection with a link of said toggle, a handle connected to another link of said toggle, a shiftable pivotal connection between links of said toggle, and a trigger for confining said connection.
48. In an electrical switch, a toggle, a movable contact member having operative connection with a link of said toggle, and a handle connected to another link of said toggle, a shiftable pivotal connection between links of said toggle, means for confining said connection and means for releasing said shiftable pivotal connection.
49. In an electrical switch, a toggle, a movable contact member having operative connection with a link of said toggle, a handle connected to another link of said toggle, a shiftable pivotal connection between links of said toggle, and electroresponsive means for controlling said shiftable connection to release said links from each other, whereby said contact member may move independently of said handle upon attempted movement of said contact member into normal position during the existence or continuance of predetermined electrical conditions.
50. In an electric switch, a movable contact member, an actuator having a slot, a member for communicating movement to said contact member and mounted for movement in said slot, and a detent adapted to engage said member for confining said member in a predetermined position in said slot.
51. In an electrical switch, a movable contact member, an actuator, having a slot, a lever for communicating movement to said contact member and mounted for movement in said slot, a trigger adapted to engage said lever for confining said lever in a predetermined position in said slot, and means for controlling said trigger.
52. In an electric switch, a movable contact member, an actuator having a slot, a lever for communicating movement to said contact member and mounted for movement in said slot, a trigger adapted to engage said lever for confining said lever in a predetermined position in said slot, and electroresponsive means for controlling said trigger.
53. In an electrical switch, a movable contact member, an actuator having a slot, a link mounted in said slot and having operative connection with said movable contact member, a trigger on said actuator for confining said link to confine it in a predetermined position in said slot, and electroresponsive means for controlling said trigger.
54. In an electrical switch, a movable contact member, an actuator having a slot, a link having operative connection with said movable contact member and movable in said slot, a trigger on said actuator adapted to engage said link to confine it in a predetermined position in said slot, and electroresponsive means for controlling said trigger, whereby said contact member may move independently of said actuator upon attempting to move said contact member into normal position during the existence or continuance of predetermined electrical conditions.
55. In an electrical switch, a toggle, a movable contact having operative connection with a link of said toggle, a handle connected to another link of said toggle, said toggle

adapted to overtravel to lock said contact member in normal position, and means for breaking operative connection between links of said toggle, whereby said contact member 5 may move independently of said handle.

56. In an electrical switch, contact-operating mechanism comprising independently-movable toggle-links, means engaging a link to confine it in operative relation with another link, said toggle being adapted to overtravel to lock the switch in normal position, and means for controlling said engaging means for breaking operative connection between said links.

57. In an electrical switch, contact-operat-

ing mechanism comprising independently-movable links, a trigger for locking said links together to form a toggle, said toggle being adapted to overtravel to lock the switch in normal position, and means for controlling 25 said trigger to break operative connection between said links.

In testimony whereof I hereunto affix my signature, in the presence of two witnesses, this 25th day of April, 1904.

FRANCIS K. FASSETT.

Witnesses:

F. R. CORNWALL;
GEORGE BAKEWELL.
